UNITED STATES PATENT OFFICE.

RICHARD R. MILLER, OF CHICAGO, ILLINOIS.

VALVE.

1,086,549.

Specification of Letters Patent.

Patented Feb. 10, 1914.

Application filed September 26, 1912. Serial No. 721,497.

To all whom it may concern:

Be it known that I, RICHARD R. MILLER, a citizen of the United States, residing at Chicago, in the county of Cook and State of Illinois, have invented a new and useful Improvement in Valves, of which the following is a specification.

The object of my invention is to provide a valve for fluids, air and gases, more simply and cheaply made, with freer passage ways, and a better seat, than valves of a like kind now in use; the particular features of which are pointed out in the following specification, and illustrated in the accompanying drawings in which:—

Figure 1, is a plan of the valve complete. Fig. 2, is an elevation, part being in section. Fig. 3, is a plan of the top member. Fig. 4, is an elevation of the part shown in Fig. 20 3. Fig. 5, is a plan of the seat broken off at the center line. Fig. 6, is a sectional elevation of the seat.

In the drawing 7 indicates the cylindrical base of the valve, externally threaded for attachment to the structure for which it is required. Above this threaded part is a projecting flange 8 which extends inwardly to a reduced part 9 of the base which is also externally threaded. Above this threaded part 9 is a table 10 adapted for the support of the removable valve seat, which is inwardly supported by the vertical elevation 11. Supported on the table 10, and by the elevation 11, is a seat 12, which is secured thereon by the top member 13. This top member is internally threaded at 14 whereby it is screwed on to the part 9, of the base 7, as shown in Fig. 2. The bottom of this top member is adapted to form a tight joint 40 with the flange 8 and the internal face 15 above the threaded portion 14, forms an inwardly inclined angle which is adapted to correspond with the angle 16, of the seat 12, whereby the seat is securely locked in position in the valve. Three ribs 17 extend vertically and then inwardly from the part 14 and are connected by rings 18, and 19, all of which constitute one integral part. The ring 19 is cylindrical. It extends above and below the junction of the ribs, and forms a cylinder 20. The external portion of the top is six sided whereby the member is screwed on to the base by means of a wrench. Slidably supported in the cylinder 20, is 55 a stem 21 of the puppet valve 22, which is adapted to rest on the seat 12, under the

pressure of a coiled spring 23, which is adapted to encircle the lower portion of the cylinder 20. Within the base 7 are two lugs 24 shown in Fig. 1 which are adapted to be engaged by a suitable tool for screwing the base into the structure desired.

The seat 12 is preferably of elastic material.

While the base is shown as an attachable member it is obvious that it may form an integral part of a structure such as a boiler, tank, pipe, dome or other connecting body.

What I claim is:—

1. A valve of the kind described consisting of a base, said base having an externally threaded portion adapted to support a top member, a table above said threaded portion and a vertical wall, said table and wall being adapted for the support of a removable seat; a seat having a base adapted to rest on said table, an internal periphery adapted to be supported by said wall and an external periphery inclined from said base upward and inward and thereby adapted to be engaged and held on said table and against said wall by a top member; a top member composed of a plurality of rings joined by a plurality of ribs, one of said rings being internally threaded and having an inwardly inclined periphery above said threaded part, whereby said member is adapted to be screwed on to the threaded portion of said base and to engage the inclined periphery of said seat and thereby lock said seat on said base, the upper ring of said top member being extended vertically and forming a vertical central cylinder; a puppet valve having a flange adapted to rest on said seat and a stem slidably supported in said cylinder; and a coiled spring encircling said cylinder and stem and compressed between the flange of said puppet valve and top ring of said top member as described.

2. In a device of the kind described the combination with a main member having an externally threaded portion for the support of a top member, a table extending inward from said threaded part, and a wall forming the inward limit of said table, said wall being adapted to support a seat; of a seat in the form of a ring adapted to be removably placed on said table and supported by said wall; a top member having an internally threaded and an inclined face above said threaded portion whereby said member is adapted to be screwed on to said main mem-

ber and on to the seat, said top member having a cylindrical center adapted to support the stem of a puppet valve and a coiled spring; a puppet valve having a stem supported in said cylindrical center of said top, and a head adapted to cover and rest on said seat, and a coiled spring compressed

within said top member on said valve as described.

RICHARD R. MILLER.
